COMBINED BOTTLE AND MEASURING CUP

Joseph G. Pacelli, Stamford, Conn., and Jerome Gould, Los Angeles, Calif.; said Pacelli assignor to Clairol Incorporated, New York, N.Y.

Filed Oct. 2, 1969, Ser. No. 19,389

Term of patent 14 years

Int. Cl. D9—01

U.S. Cl. D9—10

FIG. 1 is a perspective view of a combined bottle and measuring cup showing our new design;

FIG. 2 is a front elevational view;

FIG. 3 is a top plan view;

FIG. 4 is a side elevational view, the opposite side being a mirror image of the side shown; and

FIG. 5 is a bottom plan view thereof.

We claim:

The ornamental design for a combined bottle and measuring cup, as shown and described.
